(76) Inventors: **Walter Hunt; Willis Haskins**

October 22, 1826

Walter Hunt & William Newell
of New Haven.

The schedule referred to is in the
Letters Patent, & making part of the same
containing a description in the words of the
said, Walter Hunt & William Newell, Inventors
of their improvement in the apparatus for
finning hats or lamps.

The frame is about four feet long,
one and a half wide, & about three inches
thick, according to the size of the
fins. It is made of four plates, bent
at the joint and about four inches from
that of each. Four cross bars are inserted
in the frame, one in the middle, two on each
end, and each bar is
fastened to the sides & lower
part of each plate to the frame at a joint in each.

The main arbor is of iron, on one end
of which is the large wheel about two feet in
diameter. It is then operated by hand. There is
also a crank on the end. The small arbor
is made with two cranks.

The intermediate cylinder
or drum is about five inches in diameter
and one and a half wide. It has a number of grooves
at different angles.

The small drum or cylinder is
also made with the like grooves. The flyers
are made of iron or other metal, and are
fastened to the common drum. — The flyers are
glued and painted on the frame of either or either

The evener is constructed in the following manner: A small tube is made of iron, just the width of an inch in diameter and two inches in length, through which the thread is to pass, at each end are, therefore, on which it turns. Near the middle of the tube is a notch filed thro' the hole. - On the tube is a wheel about one inch & a half in diameter, & sufficiently wide to admit of its passing easily backward & forward, but is prevented from turning on the tube by a cog on the wheel moving in a gain or groove cut in the wheel. -

To this wheel is fixed a dog which is calculated to answer to the notch in the tube, and will press into the notch & hold it in the thread. -

There are as many eveners as there are of iron in a machine; these are placed on the iron in such a situation as to answer to the notch in the wheel, as many times as there are to a machine & the same number of flutes, or grooves, by the side of each trough. -

The troughs at one end are large enough to receive a small standard to lay, at the other end or the end over the roller they are contracted so as to admit only enough for a thread.

The small platform is about eight inches in length extending in width across the machine, with a gain for the slides which carry the eveners. The large sliding bar is a board four or five inches wide, with as many hooks attached to it as there are slides which carries the ladders. - The small sliding bar is about the width wide with as many standards as there are eveners. - The rollers are of wood and

about five inches in diameter, covered with some elastic substance and pressed together by screws. The large blades are of wood about one foot three inches in length and fitted to the fluted edge of the large platform. The small blades are about five inches in length fitted to the fluted edge of small platform.

The main arbor is placed on the middle post near the upper face, the large one being on the back side of the frame; the two hubs of the large wheel are a number of grooves.

The small arbor is placed on the large post, near the foot of each. It has a wheel with a number of grooves of different sizes, and is carried by a band from the hub of the large wheel; the crank of the small arbor is secured by a pin, passing the large wooden bar, which passes horizontally underneath the arbor, under the two side frames, and is worked by the bar passing up over the platform in front, cut for that purpose more than half together with the boards, and is fastened forward & forward.

The intermediate cylinder or drum is placed just above the lower cross bar at the right hand of the frame, and turned by a band from the large wheel. The large platform is set the top of the frame at the left hand from the road. The large arbor right hand and the small platform is set between the large platform and road.

The small cylinder or drum is placed on the lower cross cylinder under the middle side on

and is turned by the hand of the cargo, which, round this axis, turns with the frame which carries the counter, the hand being crossed so as to turn the counter, the whole going from the counter the flyers turning but with nearly the same velocity.

The flyers are placed horizontally on the side of the frame at the right hand from the counter at the end, and are turned by hands from the intermediate cylinder or drum. A small wheel is placed horizontally, nearly under the flyers, turned by a band from the hub to the large wheel, with a crank on each end which by a means of pulley, carries the small flying bar and goes to move the counter horizontally backwards, round at the same time, that the small cylinder or drum by means of the bands goes from their certain motion, so the counter are moved round. The flyers, the dog of the wheel is forced into the notch of the side and when moved back towards the side the dog is forced from the notch.

The rollers are placed near the middle of the machine at the end to the flyers and are turned by a band from a pulley, that on the small arbor having a number of grooves of different sizes. —

Between the counter and the side is a roller turning in some liquid metal which the thread is drawn over. — Immediately over the rollers is a brake which strikes the flap from the flyers and presses it between the rollers being operated by a cord attached to a lever, which is acted upon by a projecting cog in the small arbor. — in the side of each trough a slot,

The middle is a tumbler over which the ladder passes, and as it passes over the end of the glass the tumbler drives the ladder so as to fall into the glass and as the ladder falls back towards the roller the tumbler wings are not to effect the ladder. The ladder is also closed or closed by the hooks of the large sliding bar acting upon a block lever placed on the back of the ladder.

Manner of using

The clay as it comes from the brick kiln is placed in the trough, then by turning the crank each of the ladders immediately large & broken quantity of clay is spread & carried it to the rollers by means of the ladder, as the passing thro' the rollers a thread is to be drawn from each fiber passed thro' the hole in each splicer & attached to the glass already placed thro' the rollers, nothing is thought so strong but when the crank is turned the thread is to be of greater power and the ladder approaching backwards & forward saying & carrying the rollers continually a broken quantity of clay for the thread, and in so passing thro' the rollers are moving toward the ladder so as to bring the ladder to the back of the clay which has passed thro' the rollers, the in passing through the flyers each dog being forced into the notch in the side, pressed on and holds fast the threads & when the front and rear flyers are fast to their other dogs in flying at the same time taking up the threads in front as the crank draw it out and make it out. The sensible which

United States Patent

Patent No.: X4479

we particularly claim in the described machine,
are those embraced in the rolled, the beaded and
the coaxed.

Watervliet, New York, May 25th, 1876.

SIR:

The printed copies
are exhausted.

As soon as printed a copy will be mailed you to complete your order.

By direction of the Commissioner:

Very respectfully,

Chief Clerk.
